UNITED STATES PATENT OFFICE.

FRANCIS W. STEPHENSON, OF NEW YORK, AND VALENTINE MOESLEIN, OF BROOKLYN, N. Y.

SEWING-MACHINE.

SPECIFICATION forming part of Letters Patent No. 242,392, dated May 31, 1881.

Application filed July 13, 1880. (No model.)

To all whom it may concern:

Be it known that we, FRANCIS W. STEPHENSON, a citizen of the United States, residing at New York, in the county and State of New York, and VALENTINE MOESLEIN, a citizen of the German Empire, residing at Brooklyn, in the county of Kings and State of New York, have invented new and useful Improvements in Sewing-Machines, of which the following is 10 a specification.

Some parts of this invention are especially adapted to machines for sewing straw-braid or the like, while other parts are adapted to sewing-machines of ordinary construction; and it 15 consists in certain novel combinations of parts, hereinafter fully described, and pointed out in the claims.

This invention is illustrated in the accompanying drawings, in which Figure 1 represents a side elevation. Fig. 2 is a front view. Fig. 3 is a plan view of the throat-plate and feed mechanism. Figs. 4 and 5 are detail views of the eccentric as applied to the driving-shaft and feed-carrier.

25 Similar letters indicate corresponding parts. The letter A designates the machine-frame, supporting, in substantially the usual manner, the throat-plate B, the presser-foot C, and the needle-bar D, the presser-foot being equipped 30 with a lifting-cam, C', and the needle-slide being connected to a vibrating beam, D', whence it receives a reciprocating motion.

In the ordinary straw-braid sewing-machines of the Wilcox & Gibbs class, to which our 35 invention pertains, the presser-foot is lifted clear of the work at the downward movement of the needle, in order to allow the work to be turned by the operator, especially in sewing the tip or center of a hat, and to this end the 40 presser-foot has been connected to a vibrator or tipper suitably arranged on the machine.

One object of our invention is to dispense with the tipper referred to, and at the same time allow the work to be turned to any extent 45 by the operator; and to this end we construct the throat-plate B with a ridge or elevation, a, at such a part thereof that the presser-foot C acts on the work only at the point at which it is sewed, leaving the remaining portion there- 50 of free to be turned. The ridge or elevation

a extends crosswise of and the whole width of the throat-plate B, and it is situated contiguous to the needle-hole b in such plate, a portion of this hole being within one edge of the ridge, as shown in Fig. 3. The under or bearing surface of the presser-foot C is substantially flat, and hence it comes in effective contact with the work at no other point than where the work is raised by the ridge or elevation a. By our arrangement the bulk of the work is free to be 60 turned at all times during the sewing operation, and not only in the downward movement of the needle, which obviously facilitates the proper guidance of the work.

The ordinary one-part presser-foot is not practically adapted to the sewing of straw-braid, because of the difference in thickness of the work along the line of the stitching, the lapped portion being thicker or higher than the free edge of the braid which is being sewed, and 70 the presser-foot acting on one part of the work only, so that the operation of the feed mechanism is imperfect. To overcome this difficulty we attach to the presser-foot C an adjustable heel, C², adapted to act on the lapped portion 75 of the work. This heel C² is on the front part of the presser-foot, and in this example it has the shape of an inverted T, while the vertical limb thereof is slotted for the reception of a set-screw, d, whereby it is held in place.

When the machine is applied to use the work is adjusted so that the body of the presser-foot bears on the single portion or edge of the braid. The heel C² is then adjusted to the thickness 80 of the lapped braid—namely, to bear thereon—and by this means the correct operation of the feed mechanism is insured.

The feed mechanism consists of a feed surface or dog, O, attached to a feed-carrier, E, which receives the required motion from the 90 driving-shaft F, through a two-part eccentric, H H', one part of which is fixed on the shaft while the other is adjustable on the fixed part. The feed-carrier E is constructed with a sleeve, E', which is fitted on the eccentric, and with 95 a slotted arm, E², which is pivoted to the machine-frame, as at f. The outer or adjustable part, H', of the eccentric is held in place by a set-screw, g, which passes through such adjustable part and bears on the inner or fixed part, 100

H, and to which access is had through a hole, *h*, in the sleeve E'. At one end of the adjustable part H' of the eccentric is a semicircular groove, *i*, and on the fixed part H thereof is a pin, *j*, which is fitted into the groove, and by turning the part H' to bring the pin to either end of such groove a minimum or maximum degree of eccentricity is obtained.

It will be readily understood that by changing the position of the adjustable part H' of the eccentric the feed motion is changed accordingly, while the desired purpose is accomplished with a very simple contrivance.

What we claim as new, and desire to secure 15 by Letters Patent, is—

1. In a straw-braid sewing-machine, the combination, with a throat-plate having a transverse ridge projecting from its upper face adjacent to its needle-aperture, of a presser-foot 20 having a vertically-adjustable heel arranged to

act upon the lapped portion of the work, substantially as and for the purpose set forth.

2. The combination, with a driving-shaft in a sewing-machine, of the two-part eccentric composed of the inner eccentric ring H, provided with a pin, *i*, and secured upon the shaft, and the outer eccentric ring H, formed with a groove to receive the pin *i*, and secured to the inner ring by screw *g*, and the slotted arm E, provided with a sleeve, receiving the two-part eccentric, substantially as described. 25 30

In testimony whereof we have hereunto set our hands and seals in the presence of two subscribing witnesses.
